UNITED STATES PATENT OFFICE.

EBENEZER BLACKMAN, OF BROOKLYN, NEW YORK.

GAS-BURNER AND CHIMNEY.

SPECIFICATION forming part of Letters Patent No. 302,619, dated July 29, 1884.

Application filed February 26, 1883. (No model.)

To all whom it may concern:

Be it known that I, EBENEZER BLACKMAN, of Brooklyn, in Kings county, and the State of New York, have invented a certain new and 5 useful Improvement in Gas-Burners and their Chimneys, of which the following is a specification.

The improvement consists in the combination, with an annular burner, of an air-distributer, a circular deflector extending around the burner and having an indentation at a point considerably below the burner-tip, and having the upper edge turned abruptly inward at a point considerably higher than the burner-tip, 15 so as to form a circular opening, and a chimney having an indentation about three-fourths of an inch above the burner-tip.

In the accompanying drawings, Figure 1 is a sectional elevation of a gas-burner and chimney embodying my improvement, and Fig. 2 is a top view of the burner.

Similar letters of reference designate corresponding parts in both figures.

A designates a collar, which is located at 25 the bottom of the gas-burner, and provided with an internal screw-thread, whereby it may be secured to the nipple of a gas-fixture. Above the collar A a chamber, B, is located. Gas from the nipple of the gas-fixture enters this 30 chamber, and passes thence along diverging tubes C to a burner-tip, D, which is of circular form and has an annular space for the gas. The gas escapes through small perforations *a* at the top. The chamber B is provided with 35 a valve, which serves to regulate the escape of gas, and is provided with an arm, B', whereby it may be turned.

E designates a gallery in which a chimney, F, is supported. As here shown, this gallery 40 is provided at the outer edge with resilient arms, which embrace the chimney and hold it in place. This gallery may be supported from the burner-tip in any suitable manner. In this example of my invention it is formed 45 with and supported by an air-distributer, G, consisting of a finely-perforated plate. This air-distributer has its inner edge turned upward and made to fit the exterior of the burner-tip snugly. When thus made, it may be held 50 in place by friction only.

H designates a deflector fitting on the air-distributer G. It is shown as having a shoul-

der or indentation, b, opposite about the middle of the height of the burner-tip, and as having the upper edge, e, turned inward at a point considerably higher than the top of the burner-tip, so as to form a circular opening. 55 This deflector may be secured in place in any suitable manner. I have shown it as provided with lugs c, which extend laterally from its base and engage with catches d, arranged upon the air-distributer. It will be observed that the air-distributer is perforated outside as well as inside of the deflector.

All of the above-described parts, excepting 60 the chimney F, may be made of brass or other suitable metal. The chimney is of circular form, and has an indentation, f, at a point about three-fourths of an inch above the burner-tip. Above its indentation it is preferably 65 smaller in diameter than at the base portion. The chimney may be made of glass, as usual. Gas escaping from the burner-tip produces an annular flame. Air entering the air-distributer is deflected upon the flame by 70 the deflector H at a point above the burner-tip, and also by the indentation of the chimney at a point still higher. A very perfect combustion of gas, and hence a very brilliant 75 flame, is obtained in this way. The shoulder 80 b of the deflector H is advantageous, because it checks the ascension of air inside the deflector, and by causing it to impinge upon the burner-tip insures its being thoroughly heated before reaching the flame. The air admitted 85 between the deflector H and the chimney F is also heated before reaching the flame. I have found that a chimney of at least about 90 eight inches in length will be serviceable with a gas-burner like the one shown—or, in other words, a chimney extending about seven inches above the tip of the burner. I have found that the efficiency of the burner is increased 95 and a better combustion obtained by forming the chimney with an indentation at a point about three-fourths of an inch above the burner-tip. The chimney extending about seven inches above the burner-tip, and the deflector extending toward the burner-tip below the indentation in the chimney, also conduce to this 100 result.

What I claim as my invention, and desire to secure by Letters Patent, is—

The combination, with an annular burner,

of an air-distributer, a circular deflector extending around the burner and having an indentation at a point considerably below the burner-tip, and having the upper edge turned abruptly inward at a point considerably higher than the burner-tip, so as to form a circular opening and a chimney having an indentation

situated as described with reference to the burner-tip, substantially as specified.

EBENEZER BLACKMAN.
